ELECTRICAL PROTECTIVE ALARM SYSTEM

Herbert M. Laford, Allwood, N. J., assignor to
 Electro-Protective Corporation, Newark, N. J.,
 a corporation of New Jersey

Application July 27, 1946, Serial No. 686,694

7 Claims. (Cl. 177—314)

1

This invention relates to electrical protective alarm systems, such as burglar alarms.

Mercantile establishments are usually equipped with burglar alarms, and this invention has among its objects an improved electrical alarm system which is foolproof, extremely simple to test, use and supervision, and is also compact and inexpensive. A single container or housing may be provided to house all the units of the apparatus, except for the protective wiring itself which obviously must be placed in or around the door, window or other location that might provide unauthorized entry.

The foregoing and other objects of the invention will be best understood from the following description of exemplifications thereof, reference being had to the accompanying drawings wherein

Fig. 1 is a diagrammatic representation of an electrical protective alarm system according to the invention; and

Fig. 2 diagrammatically illustrates a modified apparatus of the invention.

In the apparatus of the invention, a self-contained battery is provided so as to avoid reliance on the public utilities as well as to make an external vulnerable power supply cable unnecessary. Two protection circuits are provided, one of which is permanently set to detect tampering, as, for example, with show windows, unused doorways, the housing of the burglar alarm apparatus itself, etc. The other circuit is applied to doorways that are locked for the night, for example, and is only set for night use. This arrangement enables the detection of unauthorized tampering during the day when prior art devices are normally not functioning. This tampering may be unauthorized entry into window displays, showcases, safes or the like or may merely be attempted alteration in the operation of the alarm or its controls to render them inoperative for night use. Another feature of the invention is the provision of delaying means to prevent the sounding of false alarms by transient vibrations which might momentarily open contacts.

Fig. 1 illustrates diagrammatically one form of protective alarm system of the invention. It has a control unit housing 35 containing a battery 20, a multi-blade key-operated setting switch 22, a buzzer 32 and associated wiring. An alarm bell 34 may be in a separate housing placed high upon an outside wall so as not to be easily available although easily heard by passers-by or the patrolman or watchman on his rounds. Permanent protection wiring 24 and releasable protection or tamper wiring 21 are suitably disposed on win-

2

dows as window foil lacing, on doors and in any other location that might afford unauthorized entry.

The key-controlled multi-blade setting switch 22 has two sets of contacts, three contact blades in each set and each set having a member connecting the movable ends of its blades. A cam 30 mounted on a shaft 28 is located between the sets of blades so that by rotation in one direction, the 10 "day" set of switch contact blades D1, D2 and D3 is moved to the right (as seen in the figure) and by rotation in the other direction, the "night" set of switch contact blades N1, N2, and N3 is moved to the left. In a neutral intermediate 15 position of the cam 30, as illustrated, the contact blades of switch 22 are all biased centrally toward the cam.

The control unit also includes an alarm relay 23 and a locking relay 36. When switch 22 is in 20 the neutral position shown, the battery 20 is placed in circuit with the releasable protection wiring 21, contacts D2 of switch 22, the permanent protection wiring 24 and the windings of the alarm relay 23, all in series. This circuit 25 also includes a milliammeter 25 and a variable resistance 26 enabling the current to be read and adjusted to a suitable value sufficient to actuate the armature of the alarm relay 23 and hold it away from its contact. When the switch 22 is in 30 the intermediate or "off" position shown, a capacitor 42 is placed in series with the protective circuit connected across the winding of the alarm relay 23 by means of the blade D1. When the switch 22 is placed in the "night" position 35 by rotation of the shaft 28 so that the cam 30 moves the left-hand set of contact blades to the left, the contacts of the respective switch blade pairs N1, N2 and N3 close. The N1 contact pair connects one terminal (positive) of the battery 40 with the L1 contact blade of the locking relay 36, the N2 contact pair simultaneously connecting the same battery terminal with the L2 contact of locking relay 36. The N3 contact pair is connected in series with the L3 contact pair and both 45 together establish a shunt circuit across resistor 27 connected in a circuit used for sounding an alarm at a distant central alarm station 47 located, for example, at police headquarters.

The L1 contact leads to the other (negative) 50 terminal of the battery through the windings of the locking relay 36. The L2 contact blade leads to one terminal of the outer alarm bell 34, the other terminal of which is connected to the negative terminal of the battery. The L3 contact pair 55 is used to close the circuit of the buzzer 32 in

addition to its shunting function described above.

Conventional tamper contacts 37 are inserted in the various circuits in the housing of the outer alarm bell 34, the housing of the control unit 35, as well as in the protection or tamper circuits themselves and are sensitive contacts which open upon rough handling. The tamper circuit may be affixed to a door 50, as shown. A pair of detachable contacts 51 are provided on a parting surface, one portion of each contact being fixed to the door frame and the other portion of the contact 51 fixed to the door in such a manner that closing of the door establishes a circuit through the detachable contacts 51. The upper portion of the door 50 may be glazed, a metallic foil being applied to the glazed portion. The lower panel of the door may also have a foil attached. A small gauge wire screen may be substituted for the metallic foil on the lower panel of the door. A key operated switch 52 parallels the pair of contacts 51 and functions to keep the protection circuit in the door closed even though the door is open. Other parts of the protection circuit may be similarly disposed in connection with sliding, swinging or immovable windows, transoms, ventilator openings and even drawers of safes, desks or other furniture.

Any tampering with a portion of the protection circuit such as, for example, the breaking of a foil-containing glass panel will open the tamper circuit either breaking the foil or the small gauge wire screen, opening the easily opened tamper contacts or even severance of the wiring at other points. An open tamper circuit deactivates the windings of the alarm relay 23 permitting the alarm relay armature to close the circuit through the windings of locking relay 36. All three armatures of the locking relay 36 are thus caused to close their individual circuits. The L1 contact pair maintains the windings of the locking relay energized and operated even though the open tamper circuit is closed again or the alarm relay contacts are opened. The L2 contact pair establishes the circuit to the alarm bell 34, and the L3 contact pair sets in operation the buzzer 32 and also shunts the resistor 21, thereby setting in operation the distant alarm bell 40.

The key operation of the setting switch 22 may be adjusted so that the key cannot be withdrawn unless the switch is set in either its "day" or "night" position, to insure the setting of the alarm by anyone taking the key away.

The wires in cable 60 connect the battery in the control unit 35 with the windings of the distant alarm relay 38 and the windings of the distant warning relay 39 in series through the resistor 27 and its accompanying shunt. With the resistor shunt circuit opened, the resistor 27 is so chosen or adjusted as to permit passage of sufficient current through the distant relay windings 38, 39 to actuate only the armature of the warning relay 39 and not enough to actuate the armature of the distant alarm relay 38. Warning relay 39 is selected or adjusted to raise its armature when a relatively small amount of current is passed through its windings and to keep its contacts open as long as a current at least as high as this minimum passes through its windings. The distant alarm relay 38, however, is selected or adjusted so as to be less sensitive and to raise its armature only when a larger current passes through its windings. The raising of the armature of the distant alarm relay will cause sounding of the distant alarm bell 40, whereas the dropping of the armature of the

warning relay 39 will cause sounding of the warning buzzer 41.

When the control unit is set in its "night" position and the locking relay 36 actuated as by a break in the protection circuit upon unauthorized entry into the protected premises, the distant alarm bell 40 will sound and will continue to sound until the key-operated switch 22 is moved from the "night" position. Failure of the power supply in the control unit, or open circuiting of wiring in the cable 60, or its associated wiring, will de-activate the windings of the warning relay 39 and permit its armature to close the circuit to the warning buzzer 41 from the distant power supply 68. For the provision of the local protective current through the protection circuits and operation of the alarm 34 and buzzer 32 only about 4½ or 6 volts supplied by local battery 20 are necessary. The distant alarm, however, sometimes requires higher voltage for operation through long cables in which case a separate local battery supply may be provided, operating through a separate pair of contacts in the locking relay 36.

The lines in the cable 60 are usually leased lines similar to those provided by the telephone company, and these lines are sometimes open circuited without notice.

It is understood that where the relay armatures are biased downwardly by the action of gravity and moved upwardly under the action of the activated windings, these armatures may be operated in any other manner as by being held upwardly by springs and pulled downwardly by the windings when activated. Similarly, a light may be used instead of a warning buzzer 41 to indicate when investigation of the control unit and/or cable circuits is necessary. Furthermore, although the power supply is shown by plus and minus signs to be D. C., A. C. supply may be used with equal facility and the same results with relays that respond to A. C.

The capacitor 42 on series with the protective circuit connected to the windings of alarm relay 23 serves as an electrical delaying means and prevents the sounding of false alarms caused by intermittent open circuits, such as may be produced by the vibration of doors, windows, etc. by winds, thunder, heavy traffic or the like. This action results from the ability of the capacitor to store electric charges.

With the protective current flowing through the protection circuits as adjusted by the resistor 26, a voltage appears across the terminals of the windings of the alarm relay 23 which windings have an appreciable resistance. With the switch 22 in the "night" position, the capacitor 42 is also charged with the same potential and a momentary opening in the protection circuits will cause the capacitor to discharge through the windings of the relay 23 so that it continues to hold its armature away from its contact for a very short time. The current may be about five milliamperes if the current drain on the battery 20 is to be minimized. With such small currents the useful life of the standard large size dry cells will be almost as long as the shelf life.

Setting of the switch 22 to the "day" position, with blades D1, D2, D3, thrown to the right, opens the capacitor circuit, the D2 contact pair opening the removable protection wiring circuit and the D1 contacts substituting for the capacitor 42 a resistor 44 chosen or adjusted to have a resistance approximately equal to the resistance of the removable protection wiring circuit

so as to maintain the current approximately constant regardless of the setting of the switch 22. The D3 contact pair is in parallel with the N1 contact pair and enables actuation of the locking relay 36 with the switch in the "day" position.

In the "day" setting, the buzzer 32 will function but the outer alarm bell 34 and the distant alarm will not. Such arrangement gives all the desired daytime protection and additionally permits the testing of the entire system or any portion without the embarrassment and inconvenience of the sounding of the external alarms. A manually operable switch 45 mounted inside the control unit is provided in the capacitor circuit so as to permit opening of this circuit for test purposes by authorized individuals with the switch 22 in either "night" or "off" position. The "day" operation since it is without the capacitor 42 will cause the sounding of the alarm upon such intermittent open circuits in the protection circuits as are caused by transient vibrations, as indicated above, and is useful for determining when the transient vibrations become serious enough to cause false alarms at night.

Upon the authorized opening of the protected premises in the morning, the key-operated switch 22 is set to its "off" position to interrupt the sounding of the alarm. This method of authorized entry is satisfactory when the distant alarm is not installed, but to prevent any alarm sounding upon entry, an additional key-operated switch 52 may be operated before entry to maintain the door protection circuit closed when the door is opened. The control unit may also be mounted so that the key-operated switch 22 is externally available and the switch 52 may then be dispensed with.

The above described apparatus is foolproof, simple to operate and simple to test having very few component members. The construction may be made more foolproof and simple, however, by incorporating the alarm bell 34 in the control unit thus removing some of the wiring from its vulnerable exposed location. Further simplification may be effected by providing the alarm relay 23 with another set of contacts which open the tamper circuit upon the de-activation of its winding. This causes the alarm relay to lock itself and makes it unnecessary to use a separate locking relay. The apparatus of Fig. 1 may be made more foolproof by providing additional relay means to detect short circuits, such as may sometimes be produced by the cutting of a pair of wires leading to the tamper circuits. These tamper circuits have inherent resistances or can be adjusted to have resistances of the order of several hundred ohms, and the short circuit detecting relay may be adjusted so as only to be actuated when more current flows through its windings than can flow through the relatively high resistance of the protection circuits.

Additional simplification may be effected by eliminating the central distant alarm station together with its associated wiring, the resulting apparatus being extremely compact.

Fig. 2 illustrates in simplified form the protective alarm system of Fig. 1, modified in the manner described above. It comprises a control housing 135 in which are housed a local battery 120, an open-circuit detector relay 123, a buzzer 132, and a setting switch 122 interconnected through operating circuits including rheostats 144 and 126 to the releasable protection or tamper wiring 121 and to the permanent protection or

tamper wiring 124 for operation in the manner described in connection with the corresponding elements 20, 23, 32, 22, 44, 26, 21 and 24 of Fig. 1. A capacitor 142 is arranged to be connected between the protective circuit and the winding of the alarm relay 123 by a switch 145 for operation in the manner described in connection with the capacitor 42 and switch 45 of the system of Fig. 1. The alarm device or bell 134 is shown 10 mounted within the housing 135 instead of outside thereof. The milliammeter 25 is arranged to operate in the same manner as in the system of Fig. 1.

By way of example, a protective system of the 15 type shown in Fig. 2, may be designed to give effective protection with conventional protective relays and alarm devices if the current through the two alarm detector relays 123 and 153 is adjusted to about five or six milliamperes so as 20 to be sufficient to hold in closed position the main switch contact blades of the open circuit alarm relay 123, but insufficient to close the main switch contact blades of the short circuit alarm relay 153, the latter being actuated to the closed 25 position in which it sets off the alarm, if any part of the protective circuit, including tamper circuits 121, 124, is short-circuited.

The protective system of Fig. 2 is also shown 30 provided with the additional alarm relay 153 35 connected in the protective circuit to complete an alarm circuit and set off the operation of the alarm bell 134 whenever any part of the protective circuit including the protective circuit portions 121, 124 is short-circuited. In other words, 40 in the same way as the open circuit alarm relay 123 is arranged to be actuated to the operative position for setting off the alarm when any portion of the protective wiring circuit is opened, 45 the short-circuit detecting alarm relay 153 is actuated to the operative position if portions of the protective circuit including the protection or tamper circuit portions 121, 124 are short-circuited. An additional capacitor 156 is arranged 50 to be connected in between the protective circuit and the actuating windings of the short-circuit detecting alarm relay 153 by the switch 145 in order to perform for the short-circuit alarm relay 153 the functions which the capacitor 142 performs for the open-circuit alarm relay 123. The 55 protective circuit of Fig. 2 is also arranged to be interconnected through a wire cable 160 to a distant central alarm station 147 for setting off a distant alarm device 140 in a manner analogous to that described with the corresponding elements 60, 47 and 40 of Fig. 1.

The distant alarm equipment 147 is shown 60 provided with two relays 168, 169, which control the operation of the distant alarm device 140, the operation of the two relays 168, 169 being controlled by the operation of additional switch contacts 125, 155 of the open-circuit alarm relay 123 and the short-circuit alarm relay 153. In the system of Fig. 2, the energy source, namely 65 the battery 120 of the local alarm system is utilized to control the operation of the distant alarm equipment 147. The additional blade contacts 125, 155 of the two alarm relays 123, 153, respectively, are arranged to connect a local resistor 165 in parallel with a resistor 166 connected across the leads through which the wires of cable 160 are connected at the distant alarm equipment 147 to its two operating relays 168 and 169, the windings of which are connected 70 in series with the circuit, leading by way of the 75

wires 160 and the operating elements of the local equipment 135 to the local energy source 120. In the distant alarm equipment 147, relay 168 is arranged to operate as an open-circuit detecting relay; and the relay 169 is arranged to operate as a short-circuit detecting relay, for setting off the distant alarm bell 140 whenever an open-circuit condition or short-circuit condition occurs on the protective wiring circuit, including protective wiring circuit portions 121, 124, in a manner analogous to the operation of the corresponding local alarm detecting relays 123, 153.

The current through the serially connected windings of the remote open-circuit detecting relay 168 and short-circuit detecting relay 169 is so adjusted that when the two resistances 165, 166 remain interconnected with the cable circuit 160 of the distant alarm relays, the current through the winding of the remote open-circuit alarm relay 168 will be sufficient to maintain its contacts open, and the current through the remote short-circuit alarm relay 169 will be insufficient to actuate its contacts to the closed position.

Selective operation of the local main open-circuit alarm relay 123 or short-circuit alarm detecting relay 153 will cause selective actuation of their respective contacts 125, 155 to the open position in which the circuit through the resistor 165 is open, thereby decreasing the current in the remote open-circuit relay 168 and increasing the current in the short-circuit alarm relay 169, thereby actuating their respective contacts to the closed position in which they complete an energizing circuit for the remote alarm device 140 and setting it off to sound the alarm.

With such arrangement, an open circuit on the protective or tamper circuits 121, 124 will actuate the local open-circuit detector relay 123 to the alarm position, thereby causing the setting off of the local alarm device 134 and the remote alarm device 140. In a similar manner, short-circuiting of any parts of the local protective wiring circuits 121, 124 will actuate the short-circuit detecting relay 123 to the alarm position, thereby setting into operation the local alarm device 134 and the remote alarm device 140. If desired, the remote alarm station 147 may be provided with an additional energy supply source connected across leads 178.

When using a short circuit detecting apparatus, as in Fig. 2, together with an externally operated shunting switch 52 care must be taken that the shunting line operated by the switch 52 includes a resistance approximating that of the wiring in the door 58.

The construction of the setting switch 22 of Fig. 1 and the corresponding switch 122 of Fig. 2 should be such that when moved to the "day" setting, the D3 contact pair does not make contact until after the D1 contact blade closes the protective circuit through the resistor 44 to prevent the actuation of the locking relay 36 before the protective circuit is set.

The contact blades of the setting switch 22 of the system shown in Fig. 2 should also be so designed that the extreme right-hand blade does not open its left-hand contact circuit until the protective circuit through the resistor 44 is closed.

The features and principles underlying the invention described above in connection with specific exemplifications, will suggest to those skilled in the art many other modifications thereof. For example, it appears obvious that the permanent protection circuit may be placed in parallel with

the temporary tamper circuit. The relays are then adjusted to respond to a decrease in current caused by opening one of the tamper circuits or adjusted for responding to either a decrease or increase of current to also detect the shorting of one or both of the tamper circuits. Also a single condenser shunted across the series connected windings of both relays 52 and 54 may be substituted for the two condensers of Fig. 2.

I claim:

1. In an electrical protective apparatus having a signal controlling protective wiring circuit including alarm means, part of the protective wiring circuit being arranged to be set to indicate day or night tampering and part being temporarily settable to indicate night tampering; switch means in the circuit for activating and de-activating the temporarily settable circuit; detecting relay means in the circuit responsive to open circuits in the protective wiring for closing an alarm circuit, actuating said alarm means and rendering itself inoperative to open the alarm circuit; said switch means having a setting that activates the open circuit detecting relay means to permit resetting of the apparatus; the apparatus having a self-contained source of energy and except for the protective wiring, the alarm means and circuit connections between the alarm means and the remainder of the apparatus, being contained in a tamper-proof container.

2. In an electrical protective apparatus having a signal controlling protective wiring circuit including alarm means, part of the protective wiring circuit being arranged to be set to indicate day or night tampering and part being temporarily settable to indicate night tampering; switch means in the circuit for activating and de-activating the temporarily settable circuit; detecting relay means in the circuit responsive to open circuits in the protective wiring for closing an alarm circuit, actuating said alarm means and rendering itself inoperative to open the alarm circuit; said switch means having a setting that activates the open circuit detecting relay means to permit resetting of the apparatus; the apparatus having a self-contained source of energy and except for the protective wiring, the alarm means and circuit connections between the alarm means and the remainder of the apparatus, being contained in a tamper-proof container; and delay means in the circuit that prevents actuation of the relay means by intermittent circuit changes such as those caused by shaking of doors and windows containing circuit elements from causes such as wind, thunder and heavy traffic.

3. In an electrical protective apparatus having a signal controlling protective wiring circuit including alarm means, part of the protective wiring circuit being arranged to be set to indicate day or night tampering and part being temporarily settable to indicate night tampering; switch means in the circuit for activating and de-activating the temporarily settable circuit; detecting relay means in the circuit responsive to open circuits in the protective wiring for closing an alarm circuit, actuating said alarm means and rendering itself inoperative to open the alarm circuit; relay means in the circuit responsive to short circuits in the protective wiring for closing an alarm circuit, and rendering itself inoperative to open the alarm circuit; said switch means having a setting that de-activates the short-circuit-responsive relay means and activates the open-circuit-responsive relay to permit resetting of the apparatus.

4. In an electrical protective apparatus having a signal controlling protective wiring circuit including alarm means, part of the protective wiring circuit being arranged to be set to indicate day or night tampering and part being temporarily settable to indicate night tampering: switch means in the circuit for activating and de-activating the temporarily settable circuit; detecting relay means in the circuit responsive to open circuit in the protective wiring for closing an alarm circuit, actuating said alarm means and rendering itself inoperative to open the alarm circuit; relay means in the circuit responsive to short circuits in the protective wiring for closing an alarm circuit and rendering itself inoperative to open the alarm circuit; said switch means having a setting that de-activates the short-circuit-responsive relay means and activates the open-circuit-responsive relay to permit resetting of the apparatus; and delay means in the circuit that prevents actuation of the relay means by intermittent circuit changes such as those caused by shaking of doors and windows containing circuit elements from causes such as wind, thunder and heavy traffic.

5. In an electrical protective apparatus having a signal controlling protective wiring circuit including alarm means, part of the protective wiring circuit being arranged to be set to indicate day or night tampering and part being temporarily settable to indicate night tampering: switch means in the circuit for activating and de-activating the temporarily settable circuit; detecting relay means in the circuit responsive to open circuits in the protective wiring for closing an alarm circuit, actuating said alarm means and rendering itself inoperative to open the alarm circuit; relay means in the circuit responsive to short circuits in the protective wiring for closing an alarm circuit and rendering itself inoperative to open the alarm circuit; said switch means having a setting that de-activates the short-circuit-responsive relay means and activates the open-circuit-responsive relay to permit resetting of the apparatus; said switch means being operable by key; the apparatus having a self-contained source of energy and except for the protective wiring, the alarm means and circuit connections between the alarm means and the remainder of the apparatus, being contained in a tamper-proof container.

6. In an electrical protective apparatus having a signal controlling protective wiring circuit including alarm means, part of the protective wiring circuit being arranged to be set to indicate day or night tampering and part being temporarily settable to indicate night tampering: switch means in the circuit for activating and de-activating the temporarily settable circuit; detecting relay means in the circuit responsive to open circuits in the protective wiring for closing an alarm circuit, actuating said alarm means and rendering itself inoperative to open the alarm circuit; said switch means having a setting that de-activates an alarm circuit so that the apparatus may be checked without actuating the

alarm means; said switch means being operable by key; said switch means having a setting that activates the open-circuit-responsive relay means to permit resetting of the apparatus; delay means in the circuit that prevents actuation of the relay means by intermittent circuit changes such as those caused by shaking of doors and windows containing circuit elements from causes such as wind, thunder and heavy traffic; the apparatus having a self-contained source of energy and except for the protective wiring, the alarm means and circuit connections between the alarm means and the remainder of the apparatus, being contained in a tamper-proof container.

7. In an electrical protective apparatus having a signal controlling protective wiring circuit including alarm means, part of the protective wiring circuit being arranged to be set to indicate day or night tampering and part being temporarily settable to indicate night tampering: switch means in the circuit for activating and de-activating the temporarily settable circuit; detecting relay means in the circuit responsive to open circuits in the protective wiring for closing an alarm circuit, actuating said alarm means and rendering itself inoperative to open the alarm circuit; relay means in the circuit responsive to short circuits in the protective wiring for closing an alarm circuit and rendering itself inoperative to open the alarm circuit; said switch means having a setting that de-activates an alarm circuit so that the apparatus may be checked without actuating the alarm means; said switch means being operable by key; said switch means having a setting that activates the open circuit-responsive relay means to permit resetting of the apparatus; said switch means having a setting that de-activates the short-circuit responsive relay and activates the open circuit detecting relay to permit resetting of the apparatus; delay means in the circuit that prevents actuation of the relay means by intermittent circuit changes such as those caused by shaking of doors and windows containing circuit elements from causes such as wind, thunder and heavy traffic; the apparatus having a self-contained source of energy and except for the protective wiring, the alarm means and circuit connections between the alarm means and the remainder of the apparatus, being contained in a tamper-proof container.
